UNITED STATES PATENT OFFICE.

NOEL H. LYSONS, OF MONTREAL, CANADA, ASSIGNOR TO WESTERN ELECTRIC COMPANY, INCORPORATED, OF NEW YORK, N. Y., A CORPORATION OF NEW YORK.

ELECTRICAL SWITCHING DEVICE.

Application filed September 14, 1920. Serial No. 410,154.

To all whom it may concern:

Be it known that I, NOEL H. LYSONS, a subject of the King of Great Britain, residing at 183 Wilson Avenue, in the city of 5 Montreal, Dominion of Canada, have invented certain new and useful Improvements in Electrical Switching Devices, of which the following is a full, clear, concise, and exact description.

10 This invention relates in general to electrical switching devices and more particularly to such devices used in combination with telephone hook switches.

The object of this invention is to provide 15 an auxiliary or supplemental switch structure adapted to be mounted with a switchhook and to be operable thereby, which shall be inexpensive, positive in action and durable. Other objects and advantages will appear from the further description of the 20 invention.

The invention in its preferred form consists of a mounting plate carrying contact 25 springs which plate is adapted to fit on the casing or telephone box in such manner that the contacts may be operated by the movement of the telephone switchbook lever. This invention is especially useful in converting the usual form of substation telephone wall set to a set for use on party lines 30 where a battery-saving device is used. In such sets the battery-saving device is attached to the telephone box in such a manner as to stop the upward motion of the 35 switch lever at a point approximately midway in its upward motion. The contact members are adjusted so that certain contacts are made at this mid-position, while other contacts are made upon releasing the 40 battery-saving device to allow the switchhook lever to rise to the upper limit of its travel. Usually, by means of the contacts made at the mid-position of the switchhook, the receiver is bridged across the line 45 through a condenser so that the subscriber may listen without impairing the transmission of the line, and may ascertain whether the line be idle or busy. At the further rise of the switchhook lever, the 50 transmitter circuit is closed to permit conversation by the subscriber. The device contemplated by this invention provides the additional contact means for making such circuit changes as are necessary in such a

system. No additional adjustment or alteration of the switch members is necessary.

The invention may be better understood by reference to the drawings which illustrate its preferred form.

Fig. 1 shows the invention mounted with a hook switch adapted for party line use; Fig. 2 shows a cross sectional view of the same arrangement with the switchhook depressed; Fig. 3 is a similar view with the switchhook lever in mid-position; Fig. 4 is another view of the switchhook lever released to its fully raised position. In the various views, like characters refer to like parts.

A wall member 1 of a sub-station set is 70 provided with an aperture 2 through which a switchhook lever 3 is adapted to pass. The wall member 1 is attached by means of screws 4 and 5 to a switch supporting frame 6. The switchhook lever 3 is pivotally 75 mounted on this supporting frame 6 by means of a pivot screw 7.

Mounted on the supporting frame 6 are the contact springs 8 for making the usual circuit changes in a sub-station set. Spring 80 member 9 is also mounted on the supporting member 6 and co-operates with the lever 3 to produce the usual tendency of the switchhook lever to rise when released by the removal of the receiver from the hook 85 lever 3. A battery-saving device 10 is loosely supported by the screws 5 and is provided with apertures 11 to permit motion in the said device in a direction transverse to the lever 3. Upon its initial rise, the switchhook lever 3 is prevented from rising to its fully operated position by a projection 12 provided on the member 10. When the device 10, however, is pushed back by pressure on finger piece 13, the switchhook lever 90 3 is allowed to proceed to its upper limit of motion, since the projection 12 is now removed from its path. Upon the downward movement of the lever 3, the tongue 14, which is an integral part of the device 10, 95 obstructs the motion of the lever 3 so that the device 10 is forced back into its normal position, as shown in Fig. 1.

The auxiliary switching device which is the subject of this invention consists of a 100 U-shaped plate member 15 mounted under the supporting frame 6, and held in position therewith by means of the screws 4 and 5.

This plate 15 carries a pair of contact springs 16 and 17 which are adapted to operate to perform the desired additional circuit changes. The spring member 16 terminates in a lug 18 and the spring member 17 terminates in a lug 19. The lugs 18 and 19 are of any suitable form to receive wires connecting them to the substation circuit. Spring member 17 is made longer than the spring 16 and is provided at its tip with an insulating button 20 which cooperates with the heel 21 of the lever 3 so as to receive the pressure therefrom. The springs 16 and 17 may be mounted to the mounting plate 15 in any suitable manner. As here shown, they are mounted with layers of insulating material 22 between them at their bases and secured to the mounting plate 15 by means of screws 23.

20 The contacts between the contact springs 8 and the springs 16 and 17 may be adjusted to a variety of combinations. As shown here, the springs 8 contact when the hook lever 3 is held in its mid-position by the projection 12 of the battery-saving device 10. Upon the operation of the device 10 to release the switchhook lever 3, the springs 16 and 17 will contact under the pressure of the heel 21 of the lever 3, thereby producing the 30 desired circuit changes and completing the transmitter circuit of the subscriber's set.

While the arrangement described shows perhaps the most important application in which this invention may be used, the inventor does not wish to be considered as having limited its use to this particular application. It is self-evident that this device may be adjusted so that the spring members of both the hook switch and the auxiliary switch, contact simultaneously for other purposes than that above referred to and such application is contemplated in the invention.

What is claimed is:—

1. In a telephone hook switch, a supporting wall member provided with an aperture, a hook lever adapted to swing in such aperture, a switch mounting member fastened to one side of the wall member and pivotally supporting the hook lever, a spring member to actuate the hook lever, a plurality of

contact members mounted on said switch mounting member, and controlled by said hook lever, a mounting plate secured between the wall member and the switch mounting member and a plurality of spring 55 contact members carried by said mounting plate and adapted to be actuated by the hook lever.

2. In a telephone hook switch, a supporting wall member provided with an aperture, 60 a hook lever adapted to swing in such aperture, a switch mounting member fastened to one side of the wall member and pivotally supporting the hook lever, a heel projection on the hook lever at its pivoted end, a spring 65 member supported by the switch mounting member and pressing on the heel of the hook lever to actuate the said lever, a plurality of spring contact members adapted to be actuated by the spring member, a mounting 70 plate and a plurality of spring contact members carried by the mounting plate and adapted to be actuated by the heel of the hook lever.

3. In a telephone hook switch, a supporting wall member provided with an aperture, 75 a hook lever adapted to swing in such aperture, a switch mounting member fastened to one side of the wall member and pivotally supporting the hook lever, a spring member 80 mounted on the switch mounting member to actuate the said hook lever, a heel projection on the said hook lever near its pivoted end against which heel the spring member exerts its force, a plurality of spring contact 85 members mounted on the switch mounting member and controlled by the motion of the hook lever, a mounting plate supported between the wall member and the switch mounting member, said mounting plate being provided with an aperture corresponding to the aperture in the wall member, and a pair of spring contact members carried by the said mounting plate and adapted to be operated by the heel projection of the hook 90 lever.

In witness whereof, I hereunto subscribe my name this 3rd day of August A. D., 1920.

NOEL H. LYSONS.
